UNITED STATES PATENT OFFICE

ISRAEL V. EDGERTON, OF CHICAGO, ILLINOIS, ASSIGNOR TO PALACE POULTRY CAR COMPANY, OF CHICAGO, ILLINOIS, A CORPORATION OF ILLINOIS

POULTRY CAR

Original application filed May 19, 1927, Serial No. 192,609. Divided and this application filed March 19, 1928. Serial No. 262,635.

This invention relates to the art of railway cars designed for the transportation of live stock, and has reference more particularly, as to the improvement forming the subject-matter of the invention, to what are known as poultry cars.

Poultry cars as at present constructed are usually equipped with tiers of coops disposed on opposite sides of a central longitudinal aisle, and formed with a central room or compartment constituting living and sleeping quarters for the attendant in charge of the shipment and for the storage of feed. In the upper portion of this central compartment and directly beneath the roof of the car is customarily located a water tank with pipes running therefrom toward the ends of the car for supplying water to the stock. Such water tanks are commonly provided with one or more filling spouts that extend from the top of the tank upwardly through the roof of the car, and are equipped with lids or covers.

It has heretofore proved a matter of some difficulty to make a tight, cinder-proof and water-proof joint between the filling spout or chute of the tank and the roof of the car, so as to prevent cinders and rain from getting into the latter at such joint, and the object of my present invention is to provide an improved sealed joint between the filling spout or chute and the roof of the car, such as will effectively seal the joint against the access of cinders and water from the outside, and thus prevent the access of cinders to the water tank and the rotting of the wooden roof boards around the filling spout.

This application forms a division of an application heretofore filed by me on the 19th day of May, 1927, Serial No. 192,609.

My present improvement is illustrated in the accompanying drawings, in which—

Fig. 1 is a top plan view of the central portion of the car roof directly overlying the water tank, showing the latter and a baffle therein by dotted lines beneath the roof, and showing in top plan the lids or covers of the filling spouts;

Fig. 2 is a transverse vertical section through the portion of the roof shown in

Fig. 1, with the filling spouts appearing in side elevation, and with the water tank partly broken out and in section;

Fig. 3 is an enlarged vertical section, on the line 3—3 of Fig. 1, through the car roof, the upper portion of the filling spout, and the seal and closure of the latter;

Referring to the drawings, 10 designates as an entirety the central roof portion of the poultry car, which includes the usual rafters 11 and roof boards 12. Suitably mounted by any approved means (not shown) directly beneath this central portion of the roof is the rectangular water tank designated as an entirety by 13, said tank consisting of a completely enclosed structure including a roof or cover 14, the sloping sides of which are preferably substantially parallel with the sloping sides of the car roof 10.

Disposed within the tank 13 and extending obliquely between diagonally opposite corners of the latter is a removable baffle comprising a pair of narrow flat wooden strips or planks 15 separated from each other by an intermediate space 16, and united by cross-cleats 17 nailed or otherwise secured thereto. The lower ends of the cleats 17 rest on the bottom of the tank while the ends of the baffle are fitted to diagonally opposite corners of the tank. This baffle forms in part the subject-matter of an application filed by me January 9, 1929, Serial No. 331,250, and the subject-matter of the present invention is not concerned therewith.

Mounted in the roof 14 of the tank are one or more spouts or chutes extending through the roof of the car, through which the tank is adapted to be filled from overhead. Two such filling spouts are herein shown, and since they are identical in structure, a description of one will suffice. The filling spout herein illustrated is a tapering member 19 of rectangular structure in cross-section, the lower end of which is secured in the roof 14 of the tank by a suitable gasket ring 19^a, while its upper wide end projects through a correspondingly shaped opening in the roof boards 12, fitting and projecting above said opening as shown in Fig. 3. Attached to the roof boards 12 around the projecting portion of

the spout is a sealing member consisting of a ring formed with a base portion 20 resting on the roof boards 12 and attached to the latter as by bolts 21, and an upstanding flange 22 substantially parallel with the projecting portion of the spout 19 which said flange encircles. On the upwardly projecting portion of the spout 19 is a depending channel-shaped flange 23 that embraces the upstanding flange 22 of the sealing ring. Between the upstanding flange 22 and the channel-shaped flange 23 there is interposed a channel-shaped packing 24 which effectually seals the joint between said parts, preventing the entrance of dust, cinders or water around the upper edge of the sealing ring.

The lid or cover for the filling spout or chute herein shown forms in part the subject-matter of my earlier filed application, Serial No. 192,609, and constitutes no part of the present invention, but may be briefly described as consisting of a sheet-metal plate 25 of a size to cover the upper end of the spout and flanged on three sides as shown at 25^a to overlap the flange 23; a block 26, preferably of wood, of a size to interfit the upper end of the spout, and an underlying thin metal plate 27 on the lower side of the block 26; said parts 25, 26 and 27 all being securely united by through bolts 28. To the top of the lid or cover thus formed are attached, conveniently by the same through bolts 28, a pair of hinge straps 29, the rearwardly extending ends of which are curled, as shown at 29^a in Fig. 3 to embrace a hinge pintle 30 that extends through holes in a pair of hinge lugs 31 that are welded or otherwise secured to the sealing ring 20, 22. Encircling the hinge pintle 30 between and outside the eyes 29^a of the hinge straps are spacing sleeves 32 and 33. The above described structure of lid or cover affords a very strong and snugly fitting closure for the filling spout, the edges of which are effectively sealed by reason of its overlapping engagement with the upper sealed end of the filling spout.

I claim—

1. The combination with a car roof formed with an opening and a water tank therebeneath, of a filling spout mounted in the roof of said tank filling and projecting above said car roof opening, said spout formed with an integral external depending flange on its upper end, and an angle sealing ring having a base portion resting on and attached to said car roof around the projecting portion of said spout and an upstanding flange at its upper end encircled by said depending flange and forming a dust and water proof joint with the latter.

2. The combination with a car roof formed with an opening and a water tank therebeneath, of a filling spout mounted in the roof of said tank filling and projecting above said car roof opening, said spout formed with an

integral laterally offset external depending flange on its upper end, an angle sealing ring having a base portion resting on and attached to said car roof around the projecting portion of said spout and an upstanding flange at its upper end embraced by said depending flange, and a U-shaped packing ring fitting over said upstanding flange and confined laterally between said spout and its depending flange.

ISRAEL V. EDGERTON.
